UNITED STATES PATENT OFFICE.

KARL SCHMIDT, OF ERKELENZ, GERMANY.

CONSTRUCTION OF FROZEN WALLS FOR SHAFTS IN MINES.

SPECIFICATION forming part of Letters Patent No. 768,774, dated August 30, 1904.

Application filed December 19, 1903. Serial No. 185,789. (No model.)

To all whom it may concern:

Be it known that I, KARL SCHMIDT, a citizen of Germany, residing at Erkelenz, Rhine-land, Germany, have invented certain new and 5 useful Improvements in the Construction of Frozen Walls for Shafts in Mines, of which the following is a specification.

This invention relates to a process of forming frozen walls for shafts in such a manner 10 that the freezing liquid is thoroughly utilized and an equal freezing temperature is obtained within the freezing-tubes. In this way a reliable and uniformly-frozen wall is formed, under the protection of which the shaft may 15 be sunk.

In the accompanying drawings, Figure 1 is a sectional elevation of an apparatus for carrying my invention into effect; Fig. 2, a similar view of a modification, and Fig. 3 a plan 20 of a shaft constructed according to my invention.

In practicing my invention I sink a series 25 of vertical conduits in a circle around the shaft to be constructed. Each conduit is composed of an outer pipe *a* and an inner pipe *b*, the pipes communicating with each other near the bottom of the conduit. At its upper end the pipe *a* of one conduit is connected by a 30 branch to the pipe *b* of a second conduit. The pipe *a* of this second conduit is connected to a pipe *b* of a third conduit, &c.

The freezing medium—such as liquid carbonic acid, ammonia, sulfurous acid, &c.—is 35 conveyed from a compressor (not shown) to the mouth of one of the pipes *b*. The freezing medium will descend within this pipe and enter pipe *a* at the bottom of the conduit. Thence it passes upwardly through pipe *a* to the pipe *b* of the second conduit, and so on 40 through the series.

In order to form a uniform frozen wall, I 45 arrange the conduits in a plurality of overlapping groups. With the construction shown in Fig. 3 the pipe *a* of the first conduit is coupled to the pipe *b* of the fifth conduit, while the pipe *a* of such fifth conduit is coupled to the pipe *b* of the ninth conduit, &c. In like manner the second, sixth, tenth, &c., conduits are connected and the third, seventh, eleventh,

&c., conduits, &c. The freezing medium circulating through the above groups of communicating tubes will progressively expand as it absorbs heat. The vapors which are formed during this process will escape from the last tube of each group to be reconveyed 50 to the compressor. By the arrangement described the freezing effect of one group of conduits will be reinforced by that of another overlapping group, so that soft or unfrozen zones or spaces are avoided. Furthermore, 55 the freezing medium will flow more regularly through the series of connected pipes than it would through a large number of single pipes, as was heretofore practiced.

It is of advantage that all the tubes, as well 60 as the couplings, have a uniform diameter. This insures that the wet vapors, which gradually expand, as above stated, will flow through the pipes with a constantly-increasing velocity, whereby a uniform transmission of cold 65 through the walls of the pipes is obtained.

In Fig. 2 the conduits are composed of two pipes *a* and *b*, which are arranged side by side and communicate with each other at the bottom by an elbow. The freezing medium is 70 conveyed to the first pipe *b* of one group, whence it passes through pipe *a* to the pipe *b* of a second conduit, as already described.

What I claim is—

1. Improved means for forming frozen walls 80 for shafts embracing a plurality of groups of connected freezing-tubes, and a freezing medium conveyed through said groups, substantially as specified.

2. Improved means for forming frozen walls 85 for shafts embracing a plurality of overlapping groups, each composed of connected freezing-tubes, and a freezing medium conveyed through said groups, substantially as specified.

In witness whereof I have hereunto subscribed my name in the presence of two witnesses.

KARL SCHMIDT.
